UNITED STATES PATENT OFFICE.

WILLIAM W. RAMSEY, OF CHICAGO, ILLINOIS.

CONCRETE-REINFORCING BAR.

No. 881,618.

Specification of Letters Patent. Patented March 10, 1908.

Application filed September 4, 1907. Serial No. 391,378.

To all whom it may concern:

Be it known that I, WILLIAM W. RAMSEY, a citizen of the United States, residing in Chicago, in the county of Cook and State of Illinois, have invented new and useful Improvements in Concrete-Reinforcing Bars, of which the following is a specification.

This invention is an improvement in the construction of reinforcing bars used in concrete structures and its object has been to provide a bar having the requisite strength combined with the ability to resist longitudinal movement in the concrete and to withstand the untwisting action upon it of the concrete.

The nature of the invention clearly appears in the subjoined description and also in the accompanying drawing forming a part hereof.

20 In said drawing, Figures 1 and 2 are respectively side and plan views of my improved bar; Fig. 3 is a section on the line 3—3 of Fig. 1. Fig. 4 shows the bar twisted, and Fig. 5 is a perspective showing it with the crowns of the longitudinal ridges given an irregular or wavy outline.

My improved bar preferably forms a substantially rectangular figure in cross section and it is deeply grooved lengthwise along its top and bottom, as shown in the drawing. The body of the bar is shown at 6 and the grooves at 7, 7. The grooves form ridges 8, 8 upon said top and bottom faces, and the side faces of the bar 9 are preferably concaved somewhat as appears clearly in Fig. 3. The bottoms of the grooves are desirably made sharp, though that is not an essential feature. The ridges act to give the bar great stiffness and compressive strength, as they act as trusses to the central body of the bar, and I also make them to resist any relative movement of either the bar or the concrete in directions longitudinal of the former, by twisting the bar as seen at Fig. 4. Each of the ridges is thus caused to present a continuous shoulder to the concrete throughout the whole length of the bar, and with four such shoulders resisting endwise thrust upon the bar in both directions, it will be seen that there can be no relative movement by either the bar or the concrete. My bar is also adapted to resist unwinding, as the concrete bears equally upon both sides of the wings or ridges 8, with equal force, so that

the pressure upon one side neutralizes that upon the other. The area presented to the concrete by the bar is much greater than that obtained in previous constructions, and hence the bar is rendered more efficient in proportion to the amount of metal embodied in it. 60 I also prefer to give the tops of the wings or ridges an irregular or wavy outline as seen at Fig. 5. This also tends to prevent longitudinal movement. It is also desirable that the tops of the ridges be rounded in the rolling so that they may have no tendency to split the concrete. It will be noted that the grooves 7 are deep. This renders the ridges high and gives them large contact surfaces, which are made spiral by the twisting. 70

I claim:

1. The concrete reinforcing bar consisting of an angular bar of metal and having two of its opposite sides furnished with deep central grooves forming each two longitudinal 75 ridges or wings 8 at each side of the grooves, the other two sides of the bar being substantially flat, and the bar having a solid central portion of substantially cross-sectional area between the bottoms of said grooves, sub- 80 stantially as specified.

2. The concrete reinforcing bar consisting of an angular bar of metal and having two of its opposite sides furnished with deep central grooves forming each two longitudinal 85 ridges or wings 8 at each side of the grooves, the other two sides of the bar being substantially flat, and the bar having a solid central portion of substantially cross-sectional area between the bottoms of said grooves, the 90 tops of said ridges or wings being irregular or wavy, substantially as specified.

3. The concrete reinforcing bar consisting of an angular bar of metal and having two of its opposite sides furnished with deep central 95 grooves forming each two longitudinal ridges or wings 8 at each side of the grooves, the other two sides of the bar being substantially flat, and the bar having a solid central portion of substantially cross-sectional area 100 between the bottoms of said grooves, the tops of said ridges or wings being irregular or wavy and the bar being twisted rendering the said ridges or wings spiral, substantially as specified.

4. The concrete reinforcing bar consisting of an angular bar of metal and having two of its opposite sides furnished with deep central

grooves forming each two longitudinal ridges or wings 8 at each side of the grooves, the other two sides of the bar being substantially flat, and the bar having a solid central portion of substantially cross-sectional area between the bottoms of said grooves, and said bar being twisted so as to render the said

ridges or wings spiral, substantially as specified.
